UNITED STATES PATENT OFFICE.

CHARLES MASMEJAN, OF AROGNO, TESSIN, SWITZERLAND.

ALARM-WATCH.

SPECIFICATION forming part of Letters Patent No. 311,594, dated February 3, 1885.

Application filed February 11, 1884. (Model.) Patented in France April 16, 1883, No. 154,905; in Germany November 11, 1883, No. 28,971, and in Italy December 6, 1883, XVII, 16,181, XXII, 154.

To all whom it may concern:

Be it known that I, CHARLES MASMEJAN, a citizen of the Republic of Switzerland, residing at Arogno, in the canton of Tessin, in Switzerland, have invented an Improvement 5 in Alarm-Watches, of which the following is a specification.

Letters Patent for this invention have been granted to me as follows: France, deposited April 16, 1883, granted August 3, 1883, No. 154,905; German Empire, deposited November 10, 1883, granted May 5, 1884, No. 26,971; Italy, deposited December 6, 1883, granted December 15, 1883, Vol. XVII, No. 16,181, 45 Vol. XXII, No. 158.

This invention relates to an alarm-watch in which but one spring is used to actuate the time and alarm mechanism; and my improvements relate to the means for winding up the 20 spring, to the mechanism for setting the hands and the alarm, and to the alarm mechanism, all as hereinafter described.

In the drawings, Figure 1 is a view of the front of the watch, the works being detached 25 from the case and the main and alarm dials partly removed. Fig. 2 is a view at the rear of the watch, with the cap-plate that covers the winding gear and rocker removed. Fig. 3 is an elevation of said cap-plate. Fig. 4 is 30 a diagram illustrating the gearing of the time mechanism. Fig. 5 represents the device for limiting the striking of the alarm, and Fig. 6 is an elevation of the double rocker detached.

The spring-barrel has teeth at B that gear 35 into a pinion upon the central arbor of the watch, and by the wheels 1, 2, and 3, and pinions upon the shafts of 2 and 3, motion is communicated to the escapement-wheel 4 and balance 5. This arrangement of gearing, as 40 well as the gearing for giving motion to the hour and minute hands, is of the usual character.

a is a rocker that occupies a recess in the plate b¹, and its pivot a² is at the center of 45 said plate. This rocker carries a wheel, u, that is always in gear with a wheel, v, upon a squared portion of the winding and setting stem a², and c is a spring that bears against said rocker, and moves said rocker to the left, 50 Fig. 2, and causes the wheel u to mesh with a wheel, t, upon the arbor a² of the spring-

barrel. When the wheels t and u are in gear, as shown in Fig. 2, the main spring can be wound up by turning the stem a².

b is a lever for moving the rocker-plate a to 50 the right, Fig. 2, and disconnecting the wheels t and u for a purpose hereinafter explained, and d is a cap-plate (shown detached in Fig. 3 and by dotted lines in Fig. 2) that keeps the rocker a, wheel u, and lever b in place. The 60 cap-plate d presses upon the lever b with sufficient force to hold said lever in the position to which it may be moved. In consequence of the rocker a having its center of motion at the center of the pillar-plate, the wheel u, carried by said rocker, gears with the wheels v 65 and t under the most favorable conditions.

Beneath the dial e³ of the watch there is a double-acting rocker, f, carrying the wheels g, h, i, and j, and said rocker is pivoted at d³. 70 The wheel h is upon said pivot d³, and is always in gear with the wheels v, i, and g, and the wheels i and j are upon the same stud and move as one wheel.

l and k are push-pins. Their inner ends are 75 connected with said rocker f and their outer ends project through the ring of the watch-case, so that they can be pressed upon by the finger to swing the rocker. When the pin l is pushed in, the rocker is moved and the 80 wheel j brought into gear with the minute-wheel k², and in this position the hands can be set by turning the stem a² through the medium of the wheels v, h, i, j, and k². When the finger is removed from the pin l, the spring 85 z returns the rocker to its normal position, disconnecting the wheels j and k². When the pin k is pushed in, the wheel g is brought into gear with the wheel q, and in this position the dial e⁴ can be turned for setting the alarm, the stem a² acting through the wheels v, h, g, and q.

The is a notched disk, y, connected to the wheel q by the pin 12, and said wheel q has a tubular hub surrounding the cannon of the hour-wheel and revolves with it by friction, 95 and the dial e⁴ sets upon a tubular hub of the disk y; hence the wheel q, disk y, and dial e⁴ all revolve as one with the hour-wheel once in every twelve hours, but said parts can be turned without moving said hour-wheel when the wheels g and q are in gear for setting the 100 alarm, as aforesaid. The alarm is set by turn-

ing the dial e^4 until the figure on said dial corresponding to the hour at which the alarm shall strike comes under the hour-hand of the watch.

- 5 s is a lever pivoted at 13, and the toothed end 25 of this lever is kept pressed against the edge of the disk y by the spring k' . When the lever rests against the periphery of this disk y , as shown by dotted lines in Fig. 1, the 10 other end of the lever is in the path of a pin, e' , upon the hammer e , and prevents the hammer being vibrated. When the disk has revolved so that its notch comes opposite the tooth 25, then the spring k' moves the lever 15 to the position shown by full lines in Fig. 1, the tooth passing into the notch in the disk, and at the same time the pin e' is released by that end of the lever s moving away from it. The hammer is now vibrated by the escapement-wheel s' acting upon the pins r and the 20 alarm sounded by the hammer e striking the steel wire l' . The escapement wheel s' is upon the arbor s^2 , that receives its motion from the spring-barrel through the wheels 6, 7, and 8. 25 The wheel 6 is loose upon the arbor of the spring-barrel, so as not to be revolved when the spring is being wound up; but when the lever s releases the pin e' then this wheel 6 is revolved by the ratchet-wheel a^6 , that is fast 30 to the arbor a' , acting upon the pawl 14, that is pivoted to the wheel 6. The spring-barrel is of a size to furnish six and one-half turns of winding, of which three turns are for the alarm. The balance enables the watch to run 35 for thirty hours.
- R is a finger upon the arbor of the spring-barrel, and S is a toothed segment pivoted to the plate b^6 . When the alarm is striking, the segment is turned one tooth during each revolution of the arbor a' until the segment is turned to the position shown in Fig. 4, where the further movement of the arbor a' is arrested, and the alarm stops striking. The pins r , forming the recoil-escapement, are made 40 with semi-cylindrical heads for the teeth of the escapement-wheel s' to act against, and with circular bodies entering correspondingly-shaped holes in the hammer e . By turning these pins around in their holes their adjustment is effected to regulate the working of the escapement.

- To prevent the alarm striking when the watch is in the pocket, I provide a spring, n , having a projecting part, n^4 , against which the 45 case strikes when the case is closed, thereby forcing the free end of the spring against the hammer e and preventing said hammer being moved by the escapement-wheel s' . This arrangement necessitates leaving the case open 50 when the watch is placed upon a table or other support and it is desired to have the alarm sound. The stem a^2 and wheel v revolve when the alarm strikes if the wheels u and t are in gear. It is therefore preferable to disconnect 55 these wheels u and t by the lever b , the outer end of which passes through the case and the inner end acts upon the rocker a . If the stem

is allowed to turn, its crown may catch in the watch-chain and prevent the alarm striking. If the mainspring of the watch is fully wound up, and it is desired to set the hands, then 70 the lever b must be moved to disconnect the gears u and t ; otherwise the hands cannot be set. If the spring is only partially wound up, then the act of setting the hands only winds 75 up the spring further, and there is no necessity for disconnecting the wheels u and t . In setting the alarm the stem a^2 and wheel v are turned to the left in the direction of the motion of the hands, and as this motion does not 80 wind up the spring it is immaterial whether the wheels u and t are in gear or not. The spring n might be replaced by the lever m , (shown by dotted lines in Fig. 2,) said lever to be moved by the finger to bring its inner 85 end in or out of the teeth of s' and prevent or allow the alarm to be rung, as desired.

I claim as my invention—

1. The rocker a , pivoted at the center of the watch, in combination with the wheel u , carried by said rocker, the spring-barrel and its wheel t , the stem a^2 , and wheel v , substantially as and for the purposes specified.

2. The dial e^4 , notched disk y , and wheel q upon the cannon of the hour-hand, in combination with the lever s , resting at one end against said disk y , the hammer e , having a pin passing through a slot in the watch-plate and contiguous to the outer end of said lever s , the spring k' , escapement-wheel s' , studs r on the hammer, and the sounder-spring l' , substantially as set forth.

3. The double rocker-plate f , the wheels h , i , j , and g , the stem a^2 , and wheel v , the hand-setting wheel k^2 , the alarm-dial e' , gear q , and notched disk y , substantially as set forth.

4. The combination, in an alarm-watch, of the stem-winder, the wheels for communicating motion to the spring-barrel, two wheels actuated by the spring—one to move the time-works, the other the alarm-works—the rocker-plates a and f , the gearing carried by the same, the dial e^4 , wheel q , notched disk y , lever s , hammer e , spring l' , and escapement-gearing, substantially as set forth.

5. In combination with the time and alarm mechanism, the rocker f , and wheels g , h , i , j , carried by said rocker, the wheels i and j being upon the same stud and the wheel h upon the pivot of the rocker, substantially as and for the purposes set forth.

6. The combination, with the escapement-wheel s' , of the pivoted hammer e , having pins r , r for the teeth of the wheel s' to act against, said pins being provided with circular bodies and semicircular heads, substantially as and for the purposes set forth.

Signed by me this 6th day of November, A. D. 1884.

CHARLES MASMEJAN.
